PREHEATER FOR VAPOR STOVES

Application filed April 11, 1929. Serial No. 354,215.

This invention relates to a new and improved preheater for vapor stoves and more particularly to a preheater which may be instantaneously lighted and which gives a vapor flame.

This invention relates to a preheater for types of vapor stoves which utilize gasoline, or similar volatile fluids, as a fuel, and in which the gasoline is vaporized so that it may be burned in burners adapted for the combustion of gas. Stoves of this character have required the provision of some means for preheating the generator of the stove, which generator serves to vaporize the liquid fuel.

The heating of the generator has been carried out in various ways upon starting the stove, the generator extending across one of the burners so as to be continuously heated by such burner after the stove is put into operation. In starting the stoves, various devices have been used, such as generating cups located below the generator valve which are adapted to receive liquid fuel which must be lighted to heat the generator before it is turned on to discharge vaporized fuel. In other forms of construction a small preheater generator valve has been provided, this being first heated by holding a match under it and its flame then serving to preheat the large main generator valve. Any of these forms of constructions have involved several steps by the user before the stove can be put in operation, and they are not entirely satisfactory for this reason.

It is an object of the present invention to provide a preheater valve which may be instantaneously lighted and which will serve to preheat the main generator valve.

It is a further object to provide a preheater valve of this character which derives fuel and compressed air from the pressure tank of the stove.

It is an additional object to provide a construction of this character which is simple in design and adapted for commercial production.

Other and further objects will appear as the description proceeds.

I have shown a preferred embodiment of

my invention somewhat diagrammatically in the accompanying drawings, in which—

Figure 1 is a side elevation of a portion of the assembly taken on line 1—1 of Figure 2;

Figure 2 is a plan view of the assembly;

Figure 3 is a fragmentary section taken on line 3—3 of Figure 2; and

Figure 4 is a longitudinal section of the mixing valve.

In the drawings, the pressure tank 11 is provided with a filling cap 12 and with a combined indicating meter 13 which is provided with a scale 14 and corresponding pointer to indicate the air pressure in the tank, and with a second scale 15 and corresponding pointer to indicate the quantity of fuel in the tank. The fuel supply valve 16 is secured in the top of the tank and is provided with an extension which is located within the tank and extends adjacent the bottom of the tank so that the fuel may be forced up through this extension by the air under pressure located above the fuel in the tank. This valve 16 is provided with a control handle 17 which is shown in "off" position in Figure 2. The handle 17 may be swung approximately 180° to an open position. It is not used to control the flow in amount, but merely to open and close the fuel supply valve. The fuel pipe 18 leads from the valve 16 to the T 19 from which the pipe 20 leads to the main generator valve 21.

This generator valve may be of usual construction and is provided with a control handle 22, with an intermediate tubular portion 23 which extends over the burner 24, and with a discharge end 25 adapted to discharge into the generating tube 26. The generating tube 26 is connected by distributing pipe 27 to the burner 24. It will be understood that other burners may be connected to the distributing pipe 27 and any suitable valves may be provided for controlling the flow of fuel to the various burners.

The pipe 28 also leads from the T 19 and is connected at 29 to the mixing valve 30. This mixing valve is provided with the control handle 31 and is connected by pipe 32 to the top of the tank at 33. This pipe is adapted to lead compressed air from the tank

to the mixing valve. The mixing valve 30 is connected by the short pipe 34 with the pre-heating generator 35.

This preheating generator 35 is shown in detail in Figure 3 and is provided with the valve stem 36 which is threaded into the valve body 37 at the point 38. A usual packing 39 and adjustable gland 40 are provided for preventing loss of pressure around the valve stem. The valve stem 36 is provided with the valve shoulder 41 which seats against a valve seat 42 formed in the member 37. The tubular member 43 connects the member 37 and the mixing passage 44. The valve stem 36 has a reduced extension 45 which extends through the tubular member 43 and is provided with a needle-like projection 46 which passes through the discharge orifice in the end of the tubular member 43.

20 The mixing passage 44 is formed in a small casting 47 which is located under the tubular portion 23 of the main generator. An orifice 48 is provided in the side of the casting 47 to admit additional air to be mixed with the fuel and air from the reheated generator valve 35. This mixture will then pass up out of opening 49 where it may be instantly ignited. It will then serve to heat the pre-heater valve tube 43 and also to heat the main generator valve tube 23. The casting 47 and the preheater valve casting 37 are shown as connected by a rod 50 which is threaded into the castings and serves to hold the structure rigidly together.

35 The mixing valve 30 is shown in detail in cross section in Figure 4. The valve handle 31 operates the valve stem 51 which is threaded into the valve member 52 at 53. The valve stem 51 is surrounded by packing 54 held in place by gland 55 to prevent pressure leakage. The valve shoulder 56 may be seated on the member 52 to close off flow of fuel through the pipe 28 to the preheater valve 35. The needle-like extension 57 is provided on valve 51 extending through the discharge orifice in the member 52.

50 The air tube 32 is secured to valve member 30 by the collar 58 and carries the plug 59 having a small calibrated orifice 60 to control the supply of compressed air to the mixing valve 30.

In the operation of the stove with this improved valve, the main generator valve 22 will be screwed in to close off any discharge from such valve. The main fuel control valve 17 is then turned to the "on" position which will admit a flow of fuel through pipes 18 and 28 to the mixing valve 30. Air under pressure will also flow from the tank through pipe 32 to the mixing valve and into the pre-heater generator valve body 37 through pipe 34. The air cannot flow from the preheater valve as long as the shoulder 41 is held seated. The valve shoulder 56 is first unseated in the mixing valve and then the fuel will flow with

the air to the preheater valve. The preheater valve is next unseated and the mixture of fuel and air flows from the preheater valve into the mixing passage 44. As soon as this starts to flow it may be lighted by placing a match or other lighting means adjacent the discharge orifice 49. This will cause a flame at this point which will preheat the small pre-heater valve tube 43 to insure a proper continuance of the flame, and will also serve to heat the main generator valve tube 23.

70 As soon as the tube 23 has been adequately heated the main generator valve 22 may be unscrewed to permit flow of fuel through the heated tube 23 where it will be vaporized and will pass down through the generating tube 26 and the distributing passages 27 to the burner 24. This burner may then be lighted and the mixing valve and the preheater generator valve may both be closed off.

80 This construction obviates the necessity for holding a match or other flame under the preheating valve and also avoids the necessity of having any cup or other receptacle with an open flame of liquid fuel. The construction 90 may be lighted by a match and the heater valve will very quickly heat up the main generator so that there will be very little delay in starting the main burners into operation.

95 While I have shown in detail one form of construction for carrying out my invention, this is to be understood as illustrative only as it may be carried out by other structures and in other ways, and I contemplate such changes and modifications as come within the spirit 100 and scope of the appended claims.

I claim:

1. A vapor stove construction, comprising a pressure fuel tank, a main generator valve, a burner adjacent the generator valve, a fuel supply connection between the fuel tank and main generator valve, a preheater generator valve located below the main generator valve, a mixing valve for supplying a mixture of fuel and air from said pressure fuel tank to 110 said preheater valve, an open connection between the air under pressure in the fuel tank and the mixing valve, and means for controlling the flow of fuel to the mixing valve.

115 2. A preheater for vapor stoves, comprising a preheater tube and valve, a mixing valve for supplying a mixture of fuel and air to said preheater valve, a connection between the mixing valve and preheater valve, a fuel connection to the mixing valve, a reduced orifice leading from said fuel connection to the mixing valve, a needle valve for controlling and closing said orifice, and an open air pressure connection to the mixing valve.

120 3. A preheater for vapor stoves, comprising a preheater tube and valve, a mixing valve for supplying a mixture of fuel and air to said preheater valve, a connection between the mixing valve and preheater valve, a fuel connection to the mixing valve, a reduced ori- 125

130

fice leading from said fuel connection to the mixing valve, a needle valve for controlling and closing said orifice, and an open air pressure connection to the mixing valve, the air pressure passing through the mixing valve to the preheater valve and adapted to be closed off by the preheater valve.

5 Signed at Wisconsin Rapids, Wisconsin, this 8th day of April, 1929.
